UNITED STATES PATENT OFFICE.

WILLIAM J. SCHOONOVER, OF DES MOINES, IOWA.

GEARING DEVICE FOR WASHING-MACHINES AND WRINGERS.

1,079,582.

Specification of Letters Patent.

Patented Nov. 25, 1913.

Application filed February 6, 1911. Serial No. 606,956.

To all whom it may concern:

Be it known that I, WILLIAM J. SCHOONOVER, a citizen of the United States, residing at Des Moines, in the county of Polk and State of Iowa, have invented a certain new and useful Gearing Device for Washing-Machines and Wringers, of which the following is a specification.

This invention relates to that class of gearing devices in which power is applied from a suitable motor device and this power is transmitted either to an alternating rotary agitator or to the wringer roll and the wringer rolls are provided with means whereby their movement may be reversed.

The object of my invention is to provide a gearing device of this class of simple and compact construction in which the entire gearing device is supported either upon the wringer frame or the hinged cover of the washing machine, the advantage of this construction being that both of these parts may be readily and easily handled when assembling the gearing devices and then they may be applied to the large and cumbersome tub and connected with each other readily and easily.

More specifically it is my object to provide improved and simplified means for transmitting power from a rotary driving shaft on the wringer frame to the alternating rotary agitator shaft in the washing machine cover in such a manner that the cover may be raised or lowered or held at any point of its movement without in any way affecting the operation of the agitator shaft and without throwing any gearing devices into or out of mesh.

A further object is to provide a gearing device of this kind in which the belt connected to the driving shaft and the gearing devices for operating the agitator are all arranged on the side of the machine toward which the cover is moved when being opened so that the operator may stand on the side of the machine opposite from the hinged edge of the cover and have access to the interior of the washing machine and to the wringer without danger of coming into contact with the driving belt or the agitator operating mechanism.

My invention consists in certain details, in the construction, arrangement and combination of the various parts of the device, whereby the objects contemplated are attained, as hereinafter more fully set forth,

pointed out in my claims and illustrated in the accompanying drawings, in which:

Figure 1 shows a rear elevation of a part of a washing machine and a wringer having my improved gearing device applied thereto. Fig. 2 shows a side elevation of same taken from the side toward which the hinged cover is moved when being open. Fig. 3 shows a top or plan view of a washing machine and wringer having my improved gearing device applied thereto. Fig. 4 shows a side elevation of same taken from the side opposite that from which Fig. 2 is taken. Fig. 5 shows an enlarged, detail view illustrating the segmental rack for driving the agitator shaft and the means for connecting it with the operating pitman. Fig. 6 shows a side elevation illustrating a modified form of my invention in which an electric motor and a speed reducing gear device are provided below the body of the washing machine for operating the driving shaft of the gearing mechanism, and Fig. 7 shows an enlarged, detail, sectional view illustrating the action between the pitman and the crank wheel which drives it.

Referring to the accompanying drawings, I have used the reference numeral 10 to indicate the washing machine body or tub having at its top a hinged cover 11 and a stationary cover member 12 fixed to the tub. The hinges for connecting the hinged cover member to the stationary one are provided with raised central portions, thus bringing the hinge pintles 13 a considerable distance above the top of the cover for purposes hereinafter made clear. Mounted at the center of the hinged cover is the agitator shaft 14 having a pinion 15 thereon. A segmental rack 16 is pivoted to a short shaft 17 fixed to the cover near the hinged edge thereof. Said segmental rack is provided on its side opposite from its pivotal point with an arm 18 extended outwardly and upwardly as shown in Fig. 5. It is provided at its outer end with a tubular bearing 19 and in this bearing is rotatably mounted a short shaft 20 having a forked head 21. Inserted in said forked head is a pitman 22 and a pin 23 is extended through the forked head and through the pitman to pivotally connect them. The opposite end of said pitman is screw threaded at 24 for purposes hereinafter made clear.

By the arrangement just described, it is obvious that when a reciprocating motion is

applied to the pitman 22 an alternating rotary motion will be applied to the agitator shaft 14. Furthermore on account of the raised hinges and the upwardly inclined arm 18 the hinged cover may be raised to an upright position without having the arm 18 strike upon the stationary cover member and without in any way interfering with the operation of the agitator shaft. During the raising or lowering of the cover no gearing devices of any kind are thrown either into or out of mesh, thus avoiding all possibility of breaking or injuring gear devices by throwing them into or out of gear when the cover is raised or lowered.

The wringer proper is of ordinary construction and comprises a frame 25 and two wringer rolls 26 and 27. In the construction of washing machines and wringers it is common to employ hardwood for the manufacture of the wringer frames and these frames are usually made extremely strong and durable. On the other hand it is customary to employ relatively soft wood such as cypress in the construction of washing machine tubs. It therefore is desirable to attach the gearing mechanism to the strong and durable wringer frame made of hardwood rather than to the washing machine body. I therefore apply to the wringer frame two brackets, one of which is provided with a bearing 28 for the power shaft 29 and also with an extension 30 containing a short stationary shaft 31 for the gear wheel 32. The other end of the power shaft 29 is supported by means of a bracket 33, which bracket has a bearing 34 for the power shaft 29 and a bearing 35 for a wringer driving shaft hereinafter described. These two brackets 28 and 33 are both provided with flanges 30^a which are fitted to the exterior of the washing machine body 10 and are firmly secured thereto by bolts or screws to thereby firmly unite the wringer frame to the tub. The wringer frame 25 is also secured to the tub by means of bolts or screws 31^a.

The means for transmitting power from the power shaft 29 to the pitman 22 comprises a pinion 36 rotatably mounted on the power shaft and provided with a clutch member 37. On the power shaft adjacent thereto is a sliding clutch member 38 and means are provided, as hereinafter described, for moving the sliding clutch member into or out of engagement with the rotary clutch member 37. The said pinion 36 is in mesh with the gear wheel 32. This gear wheel carries a crank pin 39 and rotatably mounted upon the crank pin is a head 40 having a screw threaded socket 41, into which the screw threaded end of the pitman 22 is seated. As shown in Fig. 7, the bearing surface of the head 40 on the crank pin 39 is slightly rounded to thereby

permit a slight movement of the socket portion 47 toward and away from the adjacent side of the gear wheel 32. By this arrangement a number of advantageous results are attained. In the first place the means for driving the agitator shaft from the power shaft 29 is of extremely simple construction. None of these parts are thrown out of gear at any time during the operation of the machine, thus danger of injury is avoided when throwing said parts into or out of gear. The cover may be freely raised or lowered whether the gear wheel 32 is being operated or is standing idle. As the cover is raised the pitman 22 is necessarily partly rotated while the socket 41 into which the pitman is screwed is held against such rotation. The provision of the screw thread at this point permits of this slight rotation and it also prevents any longitudinal movement between the socket and the pitman except a slight longitudinal movement caused by rotating the pitman relative to the socket. The movement of the outer end of the arm 18, when the cover is being raised and lowered, is almost in a straight vertical line. However it is necessarily on a segment centered at the pivotal point of the cover and therefore it is necessary to provide for a slight movement between the pitman 22 and the crank pin 39. This however can be easily provided for by making connections at the ends of the pitman with a slight amount of play.

The means for operating the wringer rolls comprises a shaft 42 mounted in the bearing 35 and having thereon two beveled pinions 43 and 44. The former is normally in mesh with a beveled pinion 45^a fixed to the power shaft 29 so that the shaft 42 is constantly rotated when the power shaft 29 is rotated. Above the beveled pinion 44 is a horizontal shaft 46, which shaft is the one on which the lower wringer roll 27 is fixed. On this shaft 46 are two beveled pinions 47 and 48, each rotatably mounted and each being in mesh with the beveled pinion 44 on opposite sides of its center. Between the beveled pinions 47 and 48 is a clutch member 49 slidably and non-rotatably mounted and capable of being brought into engagement with either of the beveled pinions 47 or 48 to thereby provide for rotating the lower wringer roll in either direction. This reverse-gearing mechanism is inclosed in a suitable casing 49^a.

For controlling the movement of the wringer rolls, I have provided an upright rod 50 mounted in a bracket 51 and provided with a spring 52 to yieldingly hold it in a downward direction. This rod is provided with a crank arm 53 in engagement with the clutch member 49 and at the top of the rod 50 is a horizontally arranged handle 54 in position to engage a notched

- bracket 55 fixed to the wringer frame. These parts are so arranged that when the handle 54 is in its neutral position, the clutch member 49 will be out of engagement with both pinions 47 and 48 and when the handle 54 is moved in either direction to its extreme position, the clutch member 49 will be in mesh with one or the other of the pinions 47 and 48.
- 10 In order to control the movement of the clutch member 38, I have provided a lever 56 fulcrumed to the wringer frame at 57 and provided with a handle 58 projected to position adjacent to the handle 54 and conveniently accessible to an operator standing at the side of the washing machine opposite the hinged edge of the cover thereof. Fixed to the wringer frame is a stationary arm 59 and in order to yieldingly hold the lever 58 in various positions of its adjustment, I provide a tension bar 60 on the lever 56 provided with a bolt 61 and a tension spring 62 on the bolt to yieldingly grip the arm 59 between the lever 58 and the tension bar 60.
- 15 When said lever 56 is in one position of its adjustment, as shown in Fig. 1, the power shaft 29 will be operated to run the wringer mechanism, which however may be thrown out of gear by the rod 50, and when in this position the gearwheel 32 will remain idle. When however the clutch member 38 is moved into engagement with the clutch member 37 the power shaft 29 will be rotated and the gear wheel 32 will also be
- 20 rotated. In order to operate the power shaft, I have provided a pulley 62^a fixed to the end of it opposite from the reverse gear mechanism for the wringer and designed to receive a belt.
- 25 In the modified form shown in Fig. 6, I have provided means for employing an electric motor to drive the power shaft. Where an electric motor is used, it is desirable to have some means for reducing the speed thereof as applied to the power shaft and for this purpose I have provided a speed reducing gearing mechanism indicated by the numeral 63 and this mechanism is connected with the power shaft by means of a belt 64 and pulleys 65 and 66.
- 30 In practice, my improved gearing device has a number of advantages in so far as the construction and assembling of the parts is concerned in that most of the gearing mechanism is permanently attached to the wringer frame which may be made strong and durable enough to withstand the strains to which the gearing device is subjected. The rest of the mechanism is connected to the hinged cover and may be applied thereto before the cover is attached to the washing machine body so that the operator in assembling the machine need only handle the wringer frame and the cover, as all of the gearing devices are attached to these parts,
- 35 and the wringer frame and cover may be attached to the washing machine in the ordinary manner and when thus attached the pitman 22 may be made to connect these parts.
- 40 That part of the gearing device which comprises the power shaft supported on the wringer frame, the gear wheel 32 driven from the power shaft, the pitman and the pivoted rack contains many advantages in practical use in devices for this purpose. First, it is of extremely simple and inexpensive construction. Second, the hinged cover may be raised and lowered at any time without danger of injury to the moving parts and regardless of whether or not the agitator shaft is running. Furthermore no gears of any kind are disconnected during this operation and hence need not be again thrown in mesh when the cover is lowered as this operation of throwing gearing devices into mesh when the cover is lowered is one that is likely to cause injury to the gear wheels.
- 45 Another advantageous feature is the arrangement of the reversing mechanism for the wringer which is supported on the same bracket on which the power shaft is mounted and hence the coacting gears on the power shaft and on the reverse mechanism are always held in mesh with each other and no strains to which the machine may be subjected will tend to alter their relative positions. It is also advantageous to group the belt wheel for the power shaft and all of the gearing mechanism for operating the agitator shaft on that side of the machine toward which the hinged cover is moved when being elevated so that an operator standing on the opposite side of the machine may have free access to the interior of the tub, and to the wringer without danger of being caught or entangled in said gearing mechanism.
- 50 In the following claims the term "main support" is used to indicate the washing machine tub or an equivalent; the word "frame" is used to indicate the frame of a wringer or its equivalent; the term "vertically arranged driven shaft" to indicate the agitator shaft; the term "horizontally arranged driven shaft" to indicate one of the wringer rolls, and the term "hinged supporting member" to indicate the cover of the tub.
- 55 I claim as my invention:
1. In a gearing device of the class described, the combination of a main support, a hinged supporting member thereon, the pivotal point of said hinges being arranged above the top of the hinged support, a vertically arranged driven shaft in the hinged support, a pinion thereon, a segmental rack in mesh with the pinion pivoted to the hinged support, said segmental rack having an arm connected therewith and extended outwardly beyond the hinged sup-

port and inclined upwardly, and a pitman connected to the outer end of said arm and being capable of universal movement relative to said arm.

5. 2. In a gearing device of the class described, the combination of a main support, a hinged supporting member thereon, the pivotal point of said hinges being arranged above the top of the hinged support, a vertically arranged driven shaft in the hinged support, a pinion thereon, a segmental rack in mesh with the pinion pivoted to the hinged support, said segmental rack having an arm connected therewith and extended 10 outwardly beyond the hinged support and inclined upwardly, a pitman connected to the outer end of said arm and being capable of universal movement relative to said arm, the end of said pitman opposite from said 15 arm being screw threaded, and a socket member having said screw threaded end seated therein, and means applied to said socket member for reciprocating the pitman.

25. 3. In a gearing device of the class described, the combination of a main support, a hinged supporting member thereon, the pivotal point of said hinges being arranged above the top of the hinged support, a vertically arranged driven shaft in the hinged support, a pinion thereon, a segmental rack in mesh with the pinion pivoted to the hinged support, said segmental rack having an arm connected therewith and extended 30 outwardly beyond the hinged support and inclined upwardly, a pitman connected to the outer end of said arm and being capable of universal movement relative to said arm, the end of said pitman opposite from said 35 arm being screw threaded, a socket member having said screw threaded end seated therein, means applied to said socket member for reciprocating the pitman, said means comprising a gear wheel having a 40 crank pin thereon, and a head on the socket member having said crank pin inserted in it.

45. 4. In a gearing device of the class described, the combination of a main support, a hinged support thereon, the hinge joint

thereof being spaced above the hinged support, a vertically arranged driven shaft in the hinged support, a pinion thereon, a segmental rack pivoted to the hinged support and in mesh with said pinion, said segmental rack having an arm connected therewith and extended outwardly beyond the hinged support and inclined upwardly, and provided at its outer end with a horizontally arranged bearing, a shaft rotatably mounted in said bearing, a forked head for the 50 shaft, a pitman mounted in said forked head and capable of pivotal movement in a horizontal plane relative to the forked head, the other end of said pitman being provided with a screw threaded portion, a socket 55 member having said screw threaded portion screwed into it to permit a slight rotary movement of the pitman relative to the socket member, a head on the socket member having a horizontally arranged opening through it, a crank wheel, and a wrist pin on the crank wheel extended through said head, for the purposes stated.

5. In a gearing device of the class described, the combination of a main support, a hinged member on the main support, a vertically arranged driven shaft in the hinged support, a pinion thereon, a segmental rack pivoted to the hinged support and in mesh with the pinion, said segmental 75 rack having an arm fixed thereon, a pitman connected to said arm, an upright frame secured to the main support, a power shaft mounted on said upright frame, a pinion on the power shaft, a pulley on the power 80 shaft, a gear wheel mounted on the upright frame and in mesh with said pinion, and a pitman connected to said gear wheel and to the arm on the segmental rack, said pitman and said pulley being both arranged on the 85 same side of the support toward which the hinged support moves when being elevated, for the purposes stated.

Des Moines, Iowa, January 23, 1911.
WILLIAM J. SCHOONOVER.
